MATERNITY PANTY GIRDLE

Marguerite R. Williams, Trumbull, Conn., assignor to Surgical Appliance, Inc., Cincinnati, Ohio, a corporation of Ohio

Filed Oct. 20, 1969, Ser. No. 19,628

Term of patent 14 years

Int. Cl. D2—02

U.S. Cl. D2—4

FIG. 1 is a side perspective view of a maternity panty girdle showing my new design;

FIG. 2 is a perspective view of the side opposite thereof;

FIG. 3 is a front elevational view thereof on a slightly reduced scale;

FIG. 4 is a side elevational view thereof; and

FIG. 5 is a rear elevational view.

I claim:

The ornamental design for a maternity panty girdle, substantially as shown.
